UNITED STATES PATENT OFFICE

HERMAN L. KUTTER, OF HAMILTON, OHIO, ASSIGNOR TO THE BLACK-CLAWSON COMPANY, OF HAMILTON, OHIO, A CORPORATION OF OHIO

PAPER-MAKING MACHINERY

Application filed December 10, 1928. Serial No. 325,038.

This invention relates to paper making machinery or the like, and more particularly to machinery of this character having means for cleaning and scraping the surface of a revolving roll or cylinder.

One object of the invention is the provision, in paper making machinery or the like, of a scraper or doctor which is normally maintained in effective scraping engagement with a roll of the machine by its own weight, the doctor being adjustably fulcrumed so the effective pressure of the doctor blade against the roll may be changed without changing the normal position of the blade.

Another object of the invention is the provision in a machine of this character of a doctor which is attached in a novel manner to reciprocating blocks or slides by means of which endwise movement of the doctor is obtained.

Other objects and advantages of the invention will be apparent from the following description and from the accompanying drawings.

In the drawings, in which like characters of reference designate like parts in the several views—

Fig. 1 is a side elevation of a paper making machine embodying the present invention;

Fig. 2 is a rear elevation of the upper portion of the machine, shown partly in section; and

Fig. 3 is a top plan view of the machine.

The invention as herein disclosed relates to paper making machinery or the like employing a doctor or scraper for cleaning or scraping the surface of a revolving roll such as a press roll or the like, the drawing disclosing the invention as applied to a paper press which receives the paper web, carried by an endless felt between the upper press roll and the lower press roll, between which considerable pressure is exerted on the web and felt to remove some of the water content from the web. As shown the machine comprises a frame 10 embodying opposite side portions 11 and 12 between which is rotatably carried the upper press roll 13. The upper press roll cooperates with a lower roll 14 rotatably journaled in bearings on a base member 15. The

base member preferably provides a support on which the frame 10 is pivoted, journals 16 being provided at opposite sides of the machine for this purpose. The frame 10 carrying the upper press roll is adapted to be moved about the axis of journals 16 by suitable hydraulic means embodying hydraulic cylinder 18 for each side of the machine, the pistons 19 of which are connected by thrust rods 20 to downwardly extending arms 21 of frame 10. By means of the hydraulic raising mechanism mentioned, the opposite ends of the upper press roll may be similarly and simultaneously moved out of engagement with the lower press roll to prevent injury to the rolls in case of week-end shut downs, and to facilitate the removal or replacement of the paper carrying felts.

In back of the upper press roll 13 the frame 10 operably carries a broke conveyor 24 shown in the form of a wide flexible endless band supported by conveyor wheels 25 and 26 and operating between guide frames 23 of any suitable character. One of the conveyor wheels is power driven by means of a suitable drive shaft 27 which is connected by a suitable sprocket drive or the like 28 to the axle 30 of the upper press roll. This broke conveyor receives the broke or scrapings from the doctor 32, the blade 33 of which engages the surface of the roll 13.

The doctor comprises a main body portion 34 preferably in the form of a hollow pipe or bar extending between opposite portions 11 and 12 of the frame. The doctor blade 33 is fixed to the outside of this body portion by means of screws 35 or the like, the blade portion of the doctor extending toward opposite sides of the body portion as shown. The blade portion 33 of the doctor is preferably substantially flat from the edge 36 where it engages the surface of the roll 13, to the rear end 37 which lies over the broke conveyor, the blade portion inclining downwardly and rearwardly as shown from its point of engagement with the roll so that the material scraped or cleaned from the surface of the roll readily travels down the inclined surface of the blade and falls on the broke 10

conveyor which then carries this material off to one side of the machine.

The end of the blade which engages the roll 13 is preferably formed as a detachable flexible strip of steel or the like of sufficient thinness so that the edge is flexible enough to follow irregularities in the surface of the roll. The effective scraping edge of the doctor being rather flexible as just mentioned, the weight of the doctor may be used to hold the blade edge in effective scraping engagement with the roll so that the latter may be effectively cleaned of any paper particles, water, or the like which might adhere to its surface. Each end of the doctor is therefore supported about an axis which lies preferably to one side of the body portion 34 of the doctor. At each end of the body portion of the doctor are a pair of pivotally interconnected members such as the clamp members 40 and 41 pivotally interconnected by a stud 42 which is threaded or otherwise fixed in one of these members and rotatably mounted in the other, these studs forming the pivotal axis about which the body portion is fulcrumed. The members 40 and 41 are shown in the form of clamps having split sides, the two lugs 43 provided at the split side of a clamp being adapted to be drawn together by a bolt 44 to clamp the member securely in place. Clamp 41 is fixed on the end of the body portion 34, the clamp 40 being securely fixed to an annular flange or boss projecting from block 45. The clamp members may be adjusted about the axis of the body portion when the bolts 44 are loosened, the latter being tightened again after the proper position of the fulcrum axis has been attained so that the weight of the body portion is effective in holding the edge of the doctor against the roll in effective scraping engagement therewith. The weight of the body portion, which is rather heavy since it must be rigid enough to carry the weight of the long doctor blade and prevent it from sagging in the middle, is thus effective to hold the scraping edge of the doctor against the roll without employing the customary loading weights or springs. Both ends of the body portion of the doctor are mounted in the manner just described, the fulcrum studs 42 being of course arranged in alignment so that the doctor is fulcrumed about a line extending parallel to but spaced from the longitudinal axis of the doctor. It will be noted that by reason of this construction adjustment in the effective pressure of the doctor blade against the roll for variation in pressure can be obtained without changing the normal position of the doctor blade or the doctor body, and without variation in the angle of inclination of the doctor blade. The pivotal fulcrum at 42 lies between vertical planes containing the scraping edge of the blade and its rear edge 37 so that

material scraped or removed from the roll by the doctor does not materially alter the effective pressure of the doctor blade, as such material when on the doctor is distributed over its entire upper surface. The angle of 70 inclination of the doctor blade is preferably such that the material which it removes from the roll readily passes along over the doctor and falls onto the broke conveyor 24.

The blocks or slides 45 which support the fixed clamps 40 are guided for movement in the frame 10 in the direction of the longitudinal axis of the doctor. As shown these blocks 45 reciprocate between the side guides 47 provided on the frame, the blocks being 80 preferably slotted as indicated at 48 so as to receive rollers 49 extending between the side guides 47 and through the slots, these rollers being rotatable upon the bolts 50 mounted in the side guides 47 and assuming 85 the weight of the blocks. One of these slide blocks 45 is adapted to be reciprocated back and forth to move the doctor and the other block in the direction of the axis of the doctor to prevent grooving of the roll. This operated block has a fork extension 52, a rotatable eccentric cam 53 operating between the fork sides 54 of this extension. The cam 53 is carried on a shaft 55 journaled at 56 and 57, shaft 55 also carrying a worm gear 58 or the like meshing with worm 59 on axle 30 of the roll 13. This roll, which is of course positively driven during operation of the machine, thus rotates the shaft 55 rather slowly and the eccentric cam 53 causes back and forth movement of the slide block 45 so that the doctor is moved back and forth as the roll rotates.

By reason of the construction described it will be apparent that the doctor may be made rather light in weight, since the entire weight of the doctor blade and body portion is effective in holding the blade edge against the roll in effective scraping engagement therewith, loading weights or the like being unnecessary. The weight of the body portion 100 and the doctor blade produces sufficient pressure on the doctor as the edge of the blade is sufficiently flexible to follow irregularities in the roll.

While the form of apparatus herein described constitutes a preferred embodiment of the invention, it is to be understood that the invention is not limited to this precise form of apparatus, and that changes may be made therein without departing from the 110 scope of the invention which is defined in the appended claims.

What is claimed is:

1. In a paper making machine of the class described, a frame, a rotatable roll supported on said frame, a doctor cooperating with said roll and comprising a body portion and a 125 blade fixed to said body portion and extending downwardly and rearwardly away from said roll, a broke conveyor extending below 130

the rear portion of said blade, said blade being inclined downwardly towards said broke conveyor, and means for pivotally supporting said doctor in an adjustable manner so its effective pressure on the roll may be varied without substantially altering the angle of inclination of the blade.

2. In a paper making machine of the class described, a frame, a rotatable roll supported on said frame, a doctor cooperating with said roll and comprising a body portion and a blade fixed to said body portion and extending downwardly and rearwardly away from said roll, a broke conveyor extending below the rear portion of said blade, said blade being substantially flat from its said rear portion to its line of engagement with the roll and inclined downwardly toward said broke conveyor, and means for pivotally supporting said doctor in an adjustable manner so its effective pressure on the roll may be varied without substantially altering the angle of inclination of the blade.

3. In a paper press, a frame, a rotatable press roll supported on said frame, a doctor cooperating with said roll and movably supported on said frame and comprising a body portion and a flexible blade fixed to said body portion and extending downwardly and rearwardly away from said roll, a broke conveyor extending below the rear portion of said blade, supporting means for pivotally supporting said body portion so that its weight is effective in holding the blade against the roll, and means for adjusting said supporting means so the effective pressure on the roll may be varied without substantially altering the normal position of the blade or body portion.

4. In a paper making machine of the class described, a frame, a rotatable roll supported on said frame, a doctor cooperating with said roll and comprising a body portion and a flexible blade fixed to said body portion, slide blocks slidably mounted on said frame at opposite sides thereof, a pair of pivotally interconnected members at each side of said doctor pivotally supporting said body portion so its weight is effective in holding the blade against the roll, one member connected to each end of said body portion and one to each of said slide blocks, means adjustably fixing said members to said slide blocks and said body portion for varying the effective pressure on said blade, and means for moving one of said slide blocks in the direction of the axis of said doctor for causing reciprocating motion of said doctor.

5. In a paper making machine of the class described, a frame, a rotatable roll supported on said frame, a doctor cooperating with said roll and comprising a body portion and a blade fixed to said body portion, slide blocks slidably mounted on said frame at opposite sides thereof, a pair of pivotally intercon-

nected members at each side of said doctor pivotally supporting said body portion so its weight is effective in holding the blade against the roll, one member connected to each end of said body portion and one to each of said slide blocks, means adjustably fixing said members to said slide blocks and said body portion for varying the effective pressure on said blade, and means for moving one of said slide blocks in the direction of the axis of said doctor for causing reciprocating motion of said doctor, said means comprising a rotatable member geared to said roll and including a rotatable cam, and a fork on said one slide block having opposed portions engaging said cam.

6. In a paper press, a press frame, a rotatable press roll operably supported on said press frame, a doctor cooperating with said roll and comprising a body portion and a blade fixed to said body portion and projecting towards opposite sides thereof, said blade having a flexible roll engaging edge and being substantially flat and inclining downwardly and rearwardly away from said roll from one end thereof to the other, a broke conveyor operably carried by said frame below the rear end of said blade, means pivotally supporting opposite ends of said body portion about an axis offset from the longitudinal axis from said body portion and located between vertical planes extending through the blade edge and the rear end of the blade, and means for adjusting the pivotal support of said body portion to vary the effective pressure of the roll while maintaining the blade in a definite normal position.

In testimony whereof I hereto affix my signature.

HERMAN L. KUTTER.
